(57) CLAIM

The ornamental design for a cosmetic bottle, as shown and described.

DESCRIPTION

FIG. 1 is a front, left perspective view from above of a cosmetic bottle.

FIG. 2 is a front elevation view of the cosmetic bottle of FIG. 1.

FIG. 3 is a rear elevation view of the cosmetic bottle of FIG. 1.

FIG. 4 is a left side elevation view of the cosmetic bottle of FIG. 1.

FIG. 5 is a right side elevation view of the cosmetic bottle of FIG. 1.

FIG. 6 is a top plan view of the cosmetic bottle of FIG. 1; and,

FIG. 7 is a bottom plan view of the cosmetic bottle of FIG. 1.

The broken lines shown illustrate portions of the cosmetic bottle that form no part of the claimed design.
